CLAIM

The ornamental design for a shim for roof and wall panels, as shown and described.

DESCRIPTION

FIG. 1 is a top, front, left perspective view of a shim for roof and wall panels showing our new design;
FIG. 2 is a right side elevation view thereof;
FIG. 3 is a left side elevation view thereof;
FIG. 4 is a rear elevation view thereof;
FIG. 5 is a front elevation view thereof;
FIG. 6 is a top plan view thereof;
FIG. 7 is a bottom plan view thereof; and,
FIG. 8 is a bottom, rear, left perspective view thereof.
The broken lines in FIGS. 1, 6, 7, and 8 depict features of the shim for roof and wall panels that form no part of the claimed design.
